UNITED STATES PATENT OFFICE.

HARRY BRIDGMAN SMITH, OF NEW YORK, N. Y., ASSIGNOR TO BRIDGMAN SMITH PATENTS COMPANY, INC., OF BROOKLYN, NEW YORK, A CORPORATION OF NEW YORK.

METHOD OF MAKING ONE-PIECE BOXES.

Application filed March 30, 1923. Serial No. 628,785.

To all whom it may concern:

Be it known that I, HARRY BRIDGMAN SMITH, a citizen of the United States, and resident of New York city, in the county of New York and State of New York, have invented certain new and useful Improvements in Methods of Making One-Piece Boxes, of which the following is a specification.

My invention relates to methods of making one-piece boxes and especially covered boxes of unitary construction, that is, boxes in which the bottom or body section and the top or cover section are connected or integral. Boxes of this class are sometimes called telescope boxes. The general object of the invention is to provide methods which materially expedite and cheapen the production of such boxes.

Generally described, the method comprises making incisions in side wall portions of an associated or assembled box shell and cover blank, folding in and securing portions of the material defined by the incisions, and folding the materials along transverse hinge lines, whereupon the bottom section telescopes within the top section, producing a complete telescope or one-piece box.

The method is devised so that it can be advantageously performed with box covering machines of a well known type, with slight modifications in such machines for the present purpose, although of course the method is also capable of being performed by hand operations or with the aid of simple instruments.

The characteristics and advantages of the invention are further sufficiently explained in connection with the following detail description of the accompanying drawings which illustrate various performances of the process. After considering these examples, persons skilled in the art will understand that many variations may be made and I do not limit myself except in accordance with the appended claims.

Figure 1 is a perspective view of one suitable form of shell blank.

Figure 2 shows the blank set up and stayed and in superposed relation to a suitable cover blank.

Figure 3 shows the shell and cover blank brought together and the cover side wings folded up.

Figure 4 shows slits cut in the cover side

wings producing flaps to be subsequently in-turned. 55

Figure 5 is a detail in section sufficiently illustrating suitable mechanism for manipulating the box parts and making the slits.

Figure 6 is a top plan detail of the slitting device. 60

Figure 7 shows the assembled blanks with the flaps turned in and secured and with side cover margins also turned in horizontally. 65

Figure 8 shows in section suitable mechanism for turning in the flaps, associated with other mechanism as commonly employed in box covering machines previously referred to. 70

Figure 9 shows a flap pressing operation.

Figure 10 shows the assembled blanks completed and the box partly folded.

Figure 11 shows the complete telescope 75 or one-piece box produced by the method steps previously illustrated.

Figure 12 shows another suitable form of shell blank set up and stayed and positioned upon a cover blank. 80

Figure 13 illustrates the operation of slitting the combined side wing materials to produce flaps which in this instance include parts of the shell and cover blanks.

Figure 14 shows the assembled blanks 85 after the slitting operation.

Figure 15 shows the flaps turned in and secured.

Figure 16 is a detail showing the operation of pressing the cover flap margins. 90

Figures 17 to 20 inclusive illustrate successive steps of producing a telescope box, from an embryo structure shown in Figure 17 which is substantially similar to a completed covered box part such as a shallow 95 walled box cover.

I will first describe a performance of the process which is well adapted for the production of boxes of this class by the use of a well known type of box covering machine, 100 slightly modified in certain respects to adapt it for the present purpose. It will be understood that the method can equally well be carried out by hand, but of course with less speed and at greater labor cost. A suitable shell blank as shown in Figure 1 comprises a body portion *a* corresponding to the bottom of the box body or lower box sec-

tion in the completed telescope box, another body portion *b* corresponding to the top of the upper or cover section in the completed box, an intermediate portion *c* corresponding to one wall of the completed box, side wing portions *e* and *e'* and end wing portions *f*. The blank has portions removed corresponding to the spaces *g*, these removed portions or spaces being opposite and co-extensive 10 with the adjacent side wing portions *e*, *e'* and wall portion *c*.

Transverse fold or hinge lines *h* are provided in the shell blank, these lines being substantially in line with the inward ends 15 of the wing portions *e* and *e'*, and defining the hinge connections between the top and bottom sections of the completed box. The lines *h* may be creased or scored in any suitable way but more desirably these lines 20 are in the form of bead creases. The production of these creases may in some cases be considered a part of the present method although otherwise the creases may be formed in the production of the complete 25 shell blanks as shown in Figure 1. The shell blank is desirably also scored along the lines *k* and *m* to facilitate folding of the side and end wings.

The shell blank is so designed that the 30 dimension *a'* of blank portion *a* is slightly less than the dimension *b'* of blank portion *b* to provide for the proper telescoping of one part or the completed box within the other.

35 The shell blank is folded or set up as shown in Figure 2 and stayed by the application of corner stays 1, and the stayed shell is then placed upon the glued upper surface of a suitable cover blank C, Fig. 2. The 40 cover blank has a central or body portion *n* co-extensive with the shell blank portions *a*, *b*, and *c*, side wings *o*, corner laps *p* and end wings *q*. The side and end wings are dimensioned so that when they are folded up 45 against the shell side and end wing portions, marginal portions 2 and 3 of the cover side and end wings *o* and *q* respectively, will project above the shell wing portions.

In the commercial production of covered 50 boxes by the use of covering machines of the class previously referred to, a glued cover blank C is placed on a movable support 10 of the covering machine, Fig. 5, with the cover wings *o* and *q* projecting beyond the support. The set-up shell blank is then placed in properly centered position on the cover blank or the set-up shell is placed on a two-part forming plunger sufficiently illustrated 55 in Fig. 5, this mechanism comprising a shallow lower plunger 11 mounted on a stem 12, and a thicker upper form or plunger 13 carried by a sleeve 14 surrounding the stem 12.

The two plungers 11 and 13 are then 60 moved down along with the support 10, and 65 in this downward movement the cover side

wings *o* are folded up and placed against the shell side wings *e* and *e'* by rollers 15. It is convenient and desirable in most cases to cut the cover side wings for the production of foldable flaps during the downward movement of the box assembly, and just after the folding up of the cover side wings as above described. For this purpose rotary cutters or slitters 16 are supported in a bracket 17, spaced suitably apart and arranged to cooperate with cutter abutments 18, Figures 5 and 6, which are secured in the upper forming plunger 13 at the sides of an aperture 19 provided in the form or plunger in adapting it for the present use. 70 75 80

The shallow lower plunger 11 has portions cut out providing spaces 20 as wide as the spaces 19, the width of these plunger spaces being slightly greater than the width of the cover flaps now to be produced or substantially co-extensive with the longitudinal dimension of the shell spaces *g*, Fig. 1. The cutting abutments 18 project inward slightly from the sides of spaces 19. The lower plunger spaces 20 are extended inward far enough to accommodate side flaps formed in the slitting operation. At the inward ends of the spaces 20 are located pressing members 21 formed on or carried by the upper plunger 13. 90 95

As the box shell and cover assembly is moved down past the cutters 16, slits 22 are cut in the cover side wings close to the adjacent ends of the shell end wings *e* and *e'*. Desirably these slits are located just beyond the ends of the shell wings as best shown in Fig. 6, so that narrow portions of the cover wing material are turned in more or less in the slitting operation to partially cover and conceal the edges of the shell material. The parallel slits 22 define flaps 24, the inner surfaces of which are covered with glue applied when the cover blank was coated all over previous to placing it on the support 10. 100 105 110 115

The support and plungers 11 and 13 now move farther down to position the box part in relation to devices for turning in the cover side wing margins 2 as shown in Figures 7 and 8. The wing margins are turned in by blades 26 secured to a reciprocating carrier 27. Before the advance of the blade carrier the upper plunger 13 is withdrawn to about the position shown in Figure 8, leaving the plunger 11 in position at the bottom of the box assembly. The carrier 27 is provided with a flap pressing member 28 having a rounded end 29 and a pressing foot 30. As the carrier advances the rounded end of the presser engages the adjacent flap 24 slightly above the bottom of the box part, and pushes it inward while plunger 13 is rising. Finally the presser foot 30 presses the flap smoothly down on an inner surface of the shell portion *o*. 120 125 130

Box covering machines of the type referred to have additional devices which now operate in proper relation to the parts already described to turn in the corner laps 5 *p*, turn up and press the end wings *q*, turn in the end wing margins 3, and then after carrier 27 has been retracted and the parts carried by it are clear of the box part, plunger 13 is moved down again, whereupon the inturned cover margins 2 and 3 10 are folded down and secured to inner surfaces of the shell. At the same time the pressing members 21 engage and press the inner ends or margins of flaps 24 firmly on the inner surfaces of shell portion *c*, as 15 shown in Fig. 9, and thereafter the two plungers are raised away from the support 10 and the box part is ejected. Fig. 10 shows the box completed except for 20 closing, and Fig. 11 shows the completed closed and telescoped box.

The box materials prior to cutting the slits 22 to form flaps 24 may conveniently be described as a box assembly or an embryo 25 box part, and the most significant features of the process as so far described consist in cutting the cover side wing material to form the flaps 24 and turning in and securing the flaps, in due relation to other 30 steps of completing the box formation which in the present instance include the completion of the cover blank application as sufficiently described above. It will be evident without further explanation how 35 the process can be carried out entirely by hand operations if desired.

Figures 12 to 16 show a variation in the process in which the shell blank has unbroken side wings *e*², and otherwise may be 40 substantially the same as in the previous instance. The shell blank is set up and stayed as before and placed on a suitable cover blank which may be the same as in the previous instance, and when the process 45 is to be carried out by a suitable machine such as the type of machine previously mentioned, the machine may be adapted for the purpose in substantially the same way. When the assembly consisting of the shell 50 and cover blank is positioned on the plungers and on support 10 and moved down past the cutters 16, the latter cut slits 22^a through both the cover side wing and the underlying shell side wing *e*² producing 55 flaps 24^a, Fig. 14, each flap consisting of combined shell and cover material with cover margins 2^a projecting beyond the ends of the shell members.

The flap turning operation is performed 60 in conjunction with the turning in of the cover margins 2 as in the previous case. The flap turning and pressing members 28 in this case simply turn the flaps in and down against shell section *c* as sufficiently 65 explained in Fig. 15, and then upon

the descent of plunger 13 the pressing members 21 engage the flap margins 2^a and press them down upon the shell to which they adhere by means of the adhesive previously applied. The covering operations are then 70 completed and the boxes folded up, producing a complete telescope box substantially like that shown in Fig. 11 except that in this instance the edges 30 of the shell side wings produced in cutting the slits 22^a 75 are not covered or concealed by margins of the adjacent cover material as may be provided for in the previous example.

The most significant features of the method in the example just explained, 80 whether performed by suitable mechanism or by hand operations, consist in cutting or slitting the combined shell and side wing materials of a box forming assembly or embryo box part, turning in and securing the flaps, and more particularly securing them by adhesive engagement of the flap cover margins with the inner surface of the shell section *c*, and then completing the formation of the one-piece or telescope covered 85 box as above sufficiently described.

Figures 17 to 20 show a variation of the process in which the box assembly or embryo box parts as shown in Figure 17, may consist of a set-up shell blank *S*² suitably 90 covered with a completely applied cover blank *B*² having the margins turned in and secured after the fashion of a complete covered box part, dimensioned of course with 95 regard to the necessary dimensions of the completed telescope or one-piece box to be produced. Transverse creases or fold lines *h* are produced on the inner shell surface defining the shell sections *a*, *b* and *c* as previously, or in some cases the hinge creases 100 may be produced in the shell blank before the application of the cover blank.

Slits 22^b are now made in the combined shell and cover side wings with due regard to the position of the fold lines *h*, adhesive 105 is applied to inner surfaces of the flaps 24^b so produced, or in some cases the adhesive could be applied to the shell surface *c*; the flaps are folded down and secured as shown in Figure 19, and the box part is then folded 110 along the hinge lines as sufficiently suggested in Fig. 20, producing a complete one-piece or telescope box substantially similar 115 to the previous example except that the turned in flaps have no projecting cover margins.

The method as last described may be understood to be performed entirely by hand operations, but if desired suitable mechanism may be employed; for example, the embryo box part as shown in Figure 17 may 120 be placed on a plunger and passed between slitting cutters arranged like the cutters 16 in Figures 5 and 6, and if a two-part plunger 125 is employed as also shown in those figures, 130

the flaps may be turned in while the upper plunger is retracted, as will be sufficiently understood from the previous explanations.

The most significant features of the process in this last example consist in cutting the combined shell and cover side wings of an embryo box part to produce flaps, the previous formation of fold lines or creases in the box part if such fold lines are not already present in the shell material, and the turning in and adhesive fastening of the flaps to inner surfaces of the shell.

I claim:

1. A method of producing a box of the class described, comprising the steps of slitting side wall material of an embryo covered box part to produce flap formations, turning in and securing the flaps.

2. A method of producing a one-piece telescope box, comprising the steps of slitting the side wall cover material of an embryo covered box part to produce flap formations, turning in and adhesively securing the flaps.

3. A method of making one-piece telescope covered boxes, comprising the steps of producing hinge lines in the shell material of an embryo box part, making parallel slits in the side wall material of the embryo covered box to produce rectangular flaps approximately at the midlength of the side walls, turning in and adhesively securing the flaps to surfaces of the shell material between the hinge lines.

4. A method of making one-piece telescope boxes, comprising the steps of producing parallel, transverse hinge lines in the box shell, making parallel slits in the side wall material of the embryo covered box part to produce flaps approximately at the midlength of the side walls and of a width approximately equal to the space between the hinge lines, turning in and adhesively securing the flaps to surfaces of the shell material between the hinge lines.

5. A method of producing one-piece or telescope boxes, comprising making parallel slits through the side wall cover material of an embryo covered box part at substantially the midlength of said walls to produce flaps of a width substantially equal to the space between parallel transverse fold lines in the embryo box body, turning in and adhesively securing the flaps to inner surfaces of the box body between the fold lines, and bending the box at the fold lines.

6. A method of producing one-piece or telescope boxes, comprising making parallel slits through the side wall shell and cover material of an embryo covered box part at substantially the midlength of said walls to produce flaps of a width substantially equal to the space between parallel trans-

verse fold lines in the embryo box body, turning in and adhesively securing the flaps to inner surfaces of the box body between the fold lines, and bending the embryo box part at the fold lines.

7. A method of producing one-piece or telescope boxes, comprising associating a set-up box shell and a glued cover blank, folding wing portions of the cover blank against side wall portions of the shell, cutting side wing portions of the cover blank on parallel lines at substantially the midlength of the assembly side walls to produce foldable flaps, and turning the flaps in and adhesively securing them to inner surfaces of the shell body.

8. A method of producing one-piece or telescope boxes, comprising associating a set-up box shell and a glued cover blank, folding wing portions of the cover blank against side wall portions of the shell, cutting side wing portions of the cover blank on parallel lines at substantially the midlength of the assembly side walls to produce foldable flaps, turning the flaps in and adhesively securing them to inner surfaces of the shell body, and completing the application of the cover blank.

9. A method of producing one-piece or telescope boxes, comprising applying a set-up and stayed box shell to a glued cover blank to produce a box-forming assembly, turning up wing portions of the cover blank against wall portions of the shell, making parallel spaced slits through combined cover and shell side wall portions approximately at the midlength of said walls to form foldable flaps consisting of combined shell and cover material, turning in the flaps and adhesively securing them on inner surfaces of the shell body.

10. A method of producing one-piece or telescope boxes, comprising applying a set-up and stayed box shell to a glued cover blank to produce a box-forming assembly, turning up wing portions of the cover blank against wall portions of the shell, producing parallel spaced slits through combined cover and shell side wall portions approximately at the midlength of said walls to form foldable flaps consisting of combined shell and cover material with glued cover margins extending beyond the ends of the shell portions, turning in the flaps and adhesively securing the projecting cover margins on inner surfaces of the shell body, completing the application of the cover blank, and folding the completed assembly into telescope box form.

Signed at New York city, in the county of New York and State of New York, this 17th day of March A. D. 1923.

HARRY BRIDGMAN SMITH.
